PROCESS AND APPARATUS FOR STITCHING

Robert T. Brauer and Edward J. Brauer,
St. Louis, Mo.

Application January 21, 1931, Serial No. 510,164

9 Claims. (Cl. 112—262)

This invention relates, generally, to sewing, and more particularly to the art of corner-stitching thin material.

Angular stitching of strips of material, such as, for instance, leather, has heretofore been readily accomplished with strips of substantial thickness; and this operation has been carried out by the use of an awl with a hook needle and a looper. It has been found, however, that thin materials cannot be stitched by such a process, and it has heretofore been impossible to corner-stitch such materials, since when the awl is withdrawn from thin materials, the material springs back so that the needle will not follow the awl hole. By the term "corner-stitching" will be understood a process in which the members to be stitched are arranged in angular relation so as to form a corner and the stitch inserted diagonally across the angle formed. The process of this invention will be understood to be of general utility, although it is especially adapted for the stitching of leather strips, such as, for instance, in the process of forming gun case pads.

The object of this invention is, generally stated, to provide a process and apparatus by which corner-stitching of thin material is possible.

A further object of this invention is to provide an inclined table for a sewing machine by means of which it is possible to corner-stitch material supported thereupon.

Other objects of this invention will become apparent to those skilled in the art when the following description is read in conjunction with the accompanying drawing, in which:—

Figure 1 is a view in end elevation of the sewing machine having a table constructed in accordance with this invention;

Figure 2 is a view in side elevation of the sewing machine of Figure 1, being shown partly in section; and

Figure 3 is a detail view of the corner of a piece of work showing in particular the disposition of the stitch therethrough.

In accordance with this invention, a sewing machine of the foot feeding type is provided with an angularly disposed table portion for supporting the work to be stitched, and to facilitate in guiding the same beneath the needle of the sewing machine. As previously stated, the process of this invention is particularly adapted to the stitching of gun case pads, and for the purpose of illustration, the description herein will be confined to the process of stitching such a gun case pad.

Referring now to the drawing, and particular-

ly to Figures 1 and 2 thereof, it will be observed that the sewing machine 1, which may be of the usual construction, is provided with a presser foot 2, having an up and down movement, and a presser foot 3, having a four direction movement. The presser foot 3 is provided with an opening 4 through the foot portion thereof, adapted to receive and guide a needle 5 in its movement. The needle 5 is of the type usually employed with sewing machines, and having an eye in the point thereof for receiving a strand of thread, such as 6. Extending beneath the presser feet 2 and 3, and adapted for engagement thereby, as well as for supporting and guiding the work to be stitched, is a table 7 having at the outer extremity thereof an inclined portion 8 for a purpose to be later described. Beneath the table 7 is provided the usual shuttle construction 9 for securing the thread 6 when inserted through the work by the needle 5.

Disposed directly beneath the presser feet 2 and 3, and in the same plane as the horizontal portion of the table 7, is a plate 11 having a slot 12 therethrough. The plate 11 extends slightly beyond the plane of the inclined portion 8 of the table, so as to form, in effect, a rib projecting from the table 7 at the intersection of the planes of the horizontal portion and the inclined portion 8.

The article to be stitched, as has been previously stated, is for the purpose of illustration a gun case pad, which consists of a strip of thin material 13 forming the bottom thereof, and a strip of thin material 14 disposed substantially at right angles to and abutting the edge of the strip 13, and it will be understood that the portion 14 is that portion which surrounds the stock of the gun, while the portion 13 overlies the butt of the gun. Disposed between the thin strips 13 and 14, as clearly illustrated in Figure 2, is a resilient pad 15, preferably formed of spongy rubber material, disposed for engagement directly with the butt plate of the gun, so as to form a cushion therefor.

In the manufacture of articles of this nature, the members 13, 14 and 15, are first glued together in their desired relation. The gluing operation is merely for the purpose of maintaining the members in their desired relative positions during the subsequent stitching process, to be now described.

The members 13, 14 and 15, after being glued in the desired relation so that a pre-arranged gun case pad is presented, are placed upon the inclined portion 8 of the sewing machine table, as clearly illustrated in Figure 2. It will be ob-

served that the member 13 of the gun case pad is provided with an extension 16, extending for a short distance beyond the member 14, which extension is left in order to facilitate the stitching operation, but which, it will be understood, is severed after the stitching operation is completed. When the gun case pad is placed upon the inclined portion 8, the presser foot 2 is brought down upon the extension 16, gripping the same 10 against the plate 11. Operation of the sewing machine is then begun.

When the sewing machine begins to operate, the presser foot 3 first moves vertically down against the member 14, pinching the corner 15 formed by the members 13 and 14, and including the resilient pad 15, therewithin, together against the plate 11. When the presser foot 3 has reached the lowermost limit of its vertical movement, the needle 5 continues to move and pierces the three 20 members at the corner thereof inserting therethrough a stitch 17, in the position illustrated in Figure 3. It is thus seen that the needle 5 is moved through the material while it is held in position not only by the gripping of presser foot 25 2, but during a time when the corner is being pinched by the pressure of foot 3 against the plate 11 to compress the resilient pad 15, and bring the thin strips 13 and 14 into substantially a parallel relation.

When the members 13, 14 and 15 have been pierced by the needle 5, and while the eye thereof is still beneath the plate 11, the presser foot 2 is moved vertically to release the grip upon the extension 16, and the presser foot 3 then moves 30 rearwardly with the needle 5, which, it will be remembered, is still inserted through the members 13, 14 and 15, to move the work laterally so that it is advanced in position for the next successive stitch. Upon the completion of this lateral movement of the work by the presser foot 3 and the needle 5, the presser foot 2 again moves downwardly to engage the extension 16 at the advanced position. In the meanwhile, the shuttle 9 has moved forward and completed the stitch 35 beneath the surface of the member 13, so that the needle 5 may now be extracted and a stitch will be left through the three pieces of material. Thus after the presser foot 2 has moved into engagement with the extension 16, the presser foot 50 3 and the needle 5 are lifted out of engagement with the work and moved forwardly into the position for the next successive stitch, in which the operations just described are repeated.

It is thus apparent that by leaving the extension 16 on the member 13 so that it may be gripped by the presser foot 2 and the plate 11, it becomes possible to maintain such an article as a gun case pad in the desired position on a sewing machine, so that the corner thereof may be 55 stitched. Furthermore, the stitching process is facilitated by pinching the materials together inside the corner, so as to bring the side and end members, that is, members 14 and 13, respectively, into a substantially parallel relation in which the 60 needle with its thread may be readily inserted.

Since it is apparent that many modifications of this invention will present themselves to those skilled in the art, which shall not depart from the spirit of this invention; and since many sub-combinations and sub-processes are of individual utility without reference to other features of this invention, it is to be distinctly understood that such modifications and the use of such sub-processes and sub-combinations, although not 65 specifically described herein, are contemplated by

and within the scope of the appended claims. It shall be furthermore understood that the embodiment herein specifically described shall be construed as merely illustrative and shall not be construed in a limiting sense. 5

Having thus described the invention what is claimed is:

1. In the art of sewing, the process comprising, arranging strips of material at an angle to each other, placing a resilient pad in the corner thus formed, pinching the pad to substantially flatten the same inside the corner and while so pinched angularly stitching the three members together with sufficient looseness that the pad may resume its natural shape upon release of the pinching pressure. 10

2. In the art of sewing, the process comprising, arranging strips of material at an angle to each other, placing a pad in the corner thus formed, pinching the pad to substantially flatten the same 20 inside the corner diagonally forcing a needle having a threaded point through the three members while so pinched, and laterally moving the needle while therein to advance the work.

3. In the art of sewing, the process comprising, arranging strips of material at an angle to each other, one of said strips having a portion extending beyond the vertex of the angle, placing a pad in the corner opposite said extended portion, gripping said extended portion, pinching the pad to 30 substantially flatten the same inside the corner and piercing the three members with a needle having a threaded point.

4. In the art of sewing, the process comprising, arranging strips of material at an angle to each other, one of said strips having a portion extending beyond the vertex of the angle, placing a pad in the corner opposite said extended portion, gripping said extended portion, pinching the corner while the extension is gripped, piercing the three 40 members at the pinched portion with a needle having a threaded point, releasing said extended portion and pinched corner, and moving said needle laterally to advance the work.

5. In the art of sewing, the process comprising, arranging strips of material at an angle to each other, one of said strips having a portion extending beyond the vertex of the angle, placing a pad in the corner opposite said extended portion, gripping said extended portion, pinching the corner 45 while the extension is gripped, piercing the three members at the pinched portion with a needle having a threaded point, releasing said extended portion and pinched corner, moving said needle laterally to advance the work, gripping said extended portion at the advanced position, and withdrawing the needle. 50

6. In the art of sewing, the process comprising, arranging strips of material at an angle to each other, one of said strips having a portion extending beyond the vertex of the angle, placing a pad in the corner opposite said extended portion, supporting the work on an inclined plane pinching the pad and strips to an extent such that a surface thereof inside the corner is substantially horizontal, and moving a needle having a threaded point 55 through the corner in a vertical plane. 60

7. In the art of sewing, the process comprising, arranging strips of material at an angle to each other, placing a resilient pad in the corner thus formed, positively pinching the members together inside the corner, forcing a needle having a threaded point through the pinched members, releasing the pinching pressure, and moving the needle laterally to advance the work. 70 75

8. In the art of sewing, the process comprising, arranging strips of material at an angle to each other, one of said strips having a portion extending beyond the vertex of the angle, placing a pad in the corner opposite said extended portion, gripping the extended portion, pinching the corner, and diagonally piercing the pinched corner with a needle having a threaded point.

9. In a machine for stitching through corners, the combination comprising, a work supporting table disposed at an angle to the horizontal ap-

proximately half the angle of the corner to be stitched, a horizontal table intersecting with the inclined table, a presser foot cooperating with the horizontal table and a second presser foot operating adjacent the intersection of the tables and disposed to pinch the corner against the tables, and a needle operating to stitch the corner while pinched.
